UNITED STATES PATENT OFFICE.

CHARLES W. LUCIUS, OF HARTWELL, OHIO.

TOY CANNON.

SPECIFICATION forming part of Letters Patent No. 484,805, dated October 25, 1892.

Application filed May 16, 1892. Serial No. 433,168. (No model.)

To all whom it may concern:

Be it known that I, CHARLES W. LUCIUS, a citizen of the United States, residing at Hartwell, in the county of Hamilton and State of Ohio, have invented a certain new and useful Toy Cannon; and I do declare the following to be a full, clear, and exact description of the invention, such as will enable others skilled in the art to which it appertains to make and use the same, reference being had to the accompanying drawings, and to the figures of reference marked thereon, which form a part of this specification.

The subject of this invention is a toy cannon; and the intention is to construct the same in such a manner as to resemble, as near as possible in manipulation and action, a real cannon, yet be devoid of all dangers inherent to the latter, so that it may be used by children and indoors.

This invention is described in the following specification, and pointed out in the claims therein, as well as illustrated in the accompanying drawings, in which—

25 Figure 1 is a perspective view, and Fig. 2 a longitudinal section, of the same.

The projectile I use consists of a wooden or hard-rubber ball which may be repeatedly used, and as a means to expel it from the cannon I employ the ordinary commercial fire or shooting cracker.

In the drawings the ball is designated by the numeral 4, and the shooting-cracker by 5.

6 is the barrel of the cannon, and 7 the touch-hole, which, unlike those in real cannons, passes clear through the barrel and also serves as a receiver for the charge, for which purpose it is substantially of a size which corresponds with a fire-cracker. Midway of its 40 height this touch-hole and receiver communicate with the bore 8 of the cannon, through which the expanding gases, after being generated by the explosion of the cracker, pass, which latter generally explodes between its 45 ends and therefore readily discharges into the bore. Inasmuch, however, as some of the direct effects of the explosion are lost, caused by a part of the gases escaping through the receiver 7, the bore 8 of the cannon is made of

50 a small diameter to concentrate as much as possible the gases which pass through it toward the muzzle for the purpose of expelling the projectile. The amount of resistance necessary to throw the ball out is provided, 55 in the absence of any wads or other means,

by the outwardly-tapering end 9 at the muzzle of the bore, into which the ball or projectile is pressed. The contracted bore prevents the ball from being inserted too tight and thereby prevents the same, by reason of 60 high resistance, from attaining a dangerous velocity, which latter, by the construction adopted, is only of a degree to throw the ball out a distance sufficient to show the effects of the powder and to make the toy interesting. A further guard against all danger or undue use is furnished by the large touch-hole and receiver 7, which pass clear through the cannon and also communicate with a passage 10 in block 11, which forms the base 70 of the cannon. This passage 10 may also be used as a means to aid in clearing the touch-hole from the remnants of the exploded cracker.

This article being intended for a cheap toy, 75 I have selected wood as the most suitable material for the same.

While a fire-cracker furnishes the most convenient charge for this cannon, it is obvious that the required amount of powder might be 80 conveyed to the receiver in any other suitable form.

Having explained my invention, I claim as new—

1. A toy cannon having an outwardly-tapering muzzle adapted to hold a ball, a contracted bore communicating with this tapering muzzle, and a combined touch-hole and receiver communicating with the bore and passing completely through the barrel of the 90 cannon, all as substantially shown and described.

2. A toy cannon having an outwardly-tapering muzzle adapted to receive a ball, a contracted bore communicating with this tapering muzzle, a combined touch-hole and receiver communicating with the bore and perforating completely the barrel of the 95 cannon, a base-block upon which the cannon is supported, and a passage through this base-block communicating with the touch-hole and receiver, all as substantially shown and described.

In testimony whereof I affix my signature in presence of two witnesses.

CHARLES W. LUCIUS.

Witnesses:

SAMUEL M. QUINN,
CHAS. SPENGEL.
